UNITED STATES PATENT OFFICE

2,090,050

SCALP MASSAGING DEVICE

Harvey F. Jackson, Brooklyn, N. Y.; Ruth W. Jackson executrix of said Harvey F. Jackson, deceased

Application December 27, 1934, Serial No. 759,331

3 Claims. (Cl. 128—67)

My invention relates to improvements in means for massaging and applying medicinal preparations to the hair and scalp, and the same has for its object to provide a device for treating the head, scalp and hair, which is simple in construction, efficient in operation, and inexpensive to manufacture.

Further, said invention has for its object to provide a device of the character specified consisting essentially of two parts which may be readily assembled for use.

Further, said invention has for its object to provide a device of the character specified of two parts, of which one serves as a receptacle or reservoir for the medicating agent, and the other as the massaging element.

Further, said invention has for its object to provide a device of the character specified in which the reservoir or receptacle portion of the device may be readily detached from the massaging element when it is desired to fill the reservoir with a medicating agent preparatory to using the device.

Further, said invention has for its object to provide a device of the character specified which is made of yielding or elastic material, and in which its cooperating parts are constructed and arranged to form a fluid-tight joint between the same when the device is in use, as well as when it is not in use.

Further, said invention has for its object to provide a device of the character specified in which the resilient receptacle is disposed within and enclosed by the cover portion, and the parts so constructed and arranged that when pressure is applied to the outer surface of the receptacle there will be a tendency of the reinforced open end to spread, which will be resisted by the flange of the cover portion, and a tight closure with the interior of the embracing flange of the cover results.

Other objects will in part be obvious and in part be pointed out hereinafter.

To the attainment of the aforesaid objects and ends, my invention consists in the novel features of construction, and in the combination, connection and arrangement of parts hereinafter more fully described and then pointed out in the claims.

50 In the accompanying drawing—

Figure 1 is a side elevation showing one form of massaging device constructed according to, and embodying my said invention; the same being shown in the hand of the user and in position for application to the scalp;

Fig. 2 is a central section taken on the line 2—2 of Fig. 3; and

Fig. 3 is a bottom view, partly broken away.

In said drawing 10 designates the device, as a whole, which is preferably made of comparatively soft rubber, and comprises a substantially semi-spherical receptacle 11 having its inner wall portion adjacent to its open end curved inwardly and downwardly to form a thickened reinforced rim portion 12, and the lower or outer face of said rim portion provided along its inner edge with an annular recess or rabbet 13. The outer side of said receptacle 11, adjacent to its open end, is provided with an annular rib or bead 14 which serves as a stop for the cover member 15, about 15 to be described, and to insure the positioning of said cover member 15 evenly along the edge or rim 12 of said receptacle.

The cover member 15 is of circular form and provided upon its flat outer surface 16 with a plurality of tapering prongs or teeth 17 formed integrally with said cover member. The cover member 15 is provided along its edge with a peripheral upwardly-extending, tapering flange or rim 18 having an annular rib or bead 19 upon its outer surface to reinforce said rim or flange 18 and to facilitate the handling of the device. The upper or free edge of said flange or rim 18 is adapted to engage with the under side of the annular rib or bead 14 of the receptacle 11.

The inner side of the cover member is concaved at 20 to render the same somewhat more resilient at that point, and said concave portion terminates in an annular shoulder 21 which corresponds to and registers with the cooperating annular recess 13 of the receptacle 11. The annular space 22 between the inner side of the flange or rim 18 and the shoulder 21 of the receptacle 11 forms an annular socket to receive the lower edge of the rim portion 12 of the receptacle 10. The inside wall of the flange or rim 18 corresponds closely in curvature with the outside surface of the rim 12 of the receptacle and forms a comparatively fluid-tight closure between said parts.

To allow for the discharge of the medicinal agent from the receptacle 11 the cover member 15 is provided at the center of its concaved portion 20 with a small, centrally-located aperture 23.

The operation of the device will be readily obvious from the foregoing description. It is to be noted, however, that when pressure is applied to the outer side of the receptacle 11, as illustrated at Figure 1, any tendency of the lower or open end of said receptacle to spread will be

resisted to some degree by the reinforced or thickened rim 12 thereof, and by the reinforced rim or flange 18 of the cover member 15, and thus insure a closure between said parts which will prevent the undue escape of fluid from the receptacle 10. The concaved central portion 20 of the cover serves to render the cover somewhat more elastic at that point so that the same may respond more readily with a pulsating movement when pressure is applied to the outer surface of the receptacle 10, as indicated at Figure 1, and the due discharge of the medicinal agent through the aperture 23 insured.

Having thus described my said invention, what I claim and desire to secure by Letters Patent is:

- 15 1. A device of the character described comprising a dish-shaped member of yieldable material including a reinforcing bead at the rim thereof and a rabbet formed in said bead about the mouth of said member, and a cover of like material having a shouldered portion interfitting with said rabbet to brace the mouth of said member and including a flange conforming to and yieldably engaging the outer surface of said member at the rim thereof and forming with said shouldered portion a groove for receiving the edge of said bead.
- 20 2. A device of the character described comprising a substantially semi-spherical hollow resilient receptacle having an opening therein
- 25
- 30

and a relatively thickened rim, said rim having a rabbet formed in the edge thereof contiguous to said opening, and a resilient cover for said receptacle having a tapering peripheral flange and a shouldered portion disposed inwardly of and in spaced relation to said flange, said flange and said shouldered portion engaging respectively with the outer side of said rim and with said rabbet, said cover having at the outer side thereof a plurality of integrally formed prongs, and an aperture extending through said cover and communicating with the interior of the receptacle.

3. A device of the character described comprising a substantially semi-spherical hollow receptacle of resilient material having an opening 15 therein and a relatively thickened rim, said rim having a shoulder formed therein at the edge thereof contiguous to said opening, and a cover of resilient material having a peripheral tapering flange and a shouldered portion disposed inwardly of and in spaced relation to said flange, said tapering flange and said shouldered portion respectively engaging with the outer side of said thickened rim and with said shoulder therein; said cover having a concave inner surface, and a 20 plurality of integrally formed prongs projecting from the outer side thereof and an aperture in said cover communicating with the interior of said receptacle.
